ATTORNEY.

UNITED STATES PATENT OFFICE.

KARL A. FERKEL, OF LOS ANGELES, CALIFORNIA.

TEMPERATURE-INDICATING MEANS.

Application filed August 26, 1925. Serial No. 52,623.

The object of my invention is to provide a new temperature indicating means, including a signal covering substance which under change of temperature will disappear and disclose the signal element. In my pending application, Serial Number 684,308, I have presented a covering matter which, under change of temperature, changes from opacity to transparency and thereby presents to view the signal element. The present invention, however, is more like a disappearing curtain for the substance is such that the predetermined temperature will cause it to disappear and uncover the signal or warning element. Another object of my invention is to provide in combination a plurality of similar signal elements, covered with substances which disappear at different temperatures, so that there can be successive indications as the temperature increases to warm, hot, and danger point. These are mentioned as illustrations, or examples, of the application of the invention for plural temperatures.

In order to more fully explain my invention, I have illustrated its embodiment in two slightly different forms on the accompanying sheet of drawings, which I will now describe.

Figure 1 is a perspective view of one embodiment of my invention, capable of being attached to an article which is subject to possible overheating, with parts broken away;

Figure 2 is a face view thereon on a smaller scale;

Figure 3 shows the invention as it might be attached to a buss bar or electric connecting member which might be overheated; and

Figure 4 shows the invention as applied to a pipe which might form an important part in a system of oil treatment or distillation and subject to possible overheating.

The invention as here illustrated comprises a body member, 1, of elongated form, having therein three pockets, or chambers, 2, 3 and 4, the back walls of which are preferably made red, as indicated by the shading. Said pockets have within them the signal or warning element, in the present showing, being the words "Warm", "Hot", and "Danger".

A covering substance is placed over these words in said pockets and so covers them that they cannot be read. In one case, the substance is one that disappears by decomposition, designated 5, and ammonium cyanide is mentioned as an example, this being

a chemical which decomposes at 36° C., the products of decomposition being gases which will pass from the pocket or disappear and thus uncover the signal element, which in this case is the word "Warm". The second pocket, 3, has therein the signal or warning element "Hot" and the covering or curtain matter is designated, 6, and beta ethyl chlorocarbonate is mentioned as the example, this being a substance which boils at 92 to 94° C. and leaves the container or pocket and uncovers the signal element. Another substance which might be used is iodine, this being a substance which sublimes or changes from the solid to a gaseous state at a temperature of 184° C. A further substance or matter which might be used where high temperature can be reached before the danger point is approached is pure metallic lead, which melts at 327° C. and if this temperature should be reached, said lead curtain or cover would melt and run off of the signal element so as to expose the same and give the indication or evidence that such high temperature had been reached.

For purposes of this application, either the iodine, or pure metallic lead, can be indicated as a cover, 7, in pocket 4, depending on which temperature is desired to be the predetermined temperature at which the warning or signal should be given.

In all these cases, it is to be noted that when the predetermined temperature is reached, the covering substance is caused to disappear from the signal element and to uncover and expose said signal or warning element.

The device may be made with a transparent cover, as 8, over each pocket, and with attaching ears, as 9, 9, or with spring clips, 10, 10, indicated in light broken lines for the purpose of attaching the same, to a flat object, 11, which might be a buss bar or other electric connecting member, or to a pipe, 12, in any system in which the temperatures reached are registered in said pipe.

While I have shown and described certain embodiments or applications of my invention, it is to be understood that these have been shown for explanatory and illustrative purposes, and I do not limit my invention except as I may be limited by the hereto appended claims.

I claim:

1. Temperature indicating means of the character referred to including a container

- having therein a plurality of different chambers, a colored signal element associated with each chamber, a covering substance in each of said chambers normally hiding from view said signal element, said substances being capable of changing their form so as to expose to view said signal elements covered thereby, and requiring different temperatures to cause said change in form, whereby to indicate that one temperature has been reached and another has not been reached.
2. Temperature indicating means consisting of a casing adapted to be placed against a surface subject to change of temperature, said casing having therein a plurality of different chambers with transparent covers, means back of said covers to serve as signals when exposed to view, a substance in each of said chambers and normally covering said signal means, said substances each being capable of change of form to expose said signal means to view and each requiring a different temperature to effect such change, whereby said device is operable to indicate that a temperature has been reached between that required to change one substance and that required to change another of said substances.
3. A device specially designed to indicate change in temperature and having a chamber, a substance in said chamber which is normally opaque and possessing the characteristic of changing its form by rise in temperature from opaqueness to gaseous form, and a signal element covered by said substance and hidden from view while said substance remains in its opaque form and exposed to view when said substance changes its form to a gaseous condition by reason of the rise in temperature.
4. A device specially designed to indicate change in temperature including a substance placed to hide from view a signal element, a signal element, said substance releasing itself through a chemical change when a certain temperature is reached, thereby exposing said signal element to view.
5. A device specially designed to indicate change in temperature including a substance placed to hide from view a signal element, a signal element, said substance releasing itself through a physical change when a certain temperature is reached, thereby exposing said signal element to view.

Signed at Los Angeles, Los Angeles County, California, this 21st day of Aug., 1925.

KARL A. FERKEL
